E. PARKER.

Stovepipe Damper.

No. 64.136.

Patented April 23, 1867.

United States Patent Office.

EPHRAIM PARKER, OF MARLOW, NEW HAMPSHIRE.

Letters Patent No. 64,136, dated April 28, 1867.

STOVE-PIPE DAMPER.

The Schedule referred to in these Letters Patent and making part of the same.

TO ALL WHOM IT MAY CONCERN:

Be it known that I, EPHRAIM PARKER, of Marlow, county of Cheshire, and State of New Hampshire, have invented a new and useful improvement in radiators or dampers, called the Self-Adjusting Damper. I do hereby declare that the following is a full, clear, and exact description of the construction and operation of the same, reference being had to the accompanying drawing, and to the letters of reference marked theron, making part of this specification, in which—

Figure 1 is a top view of the damper.

Figure 2 is a section in line of xx of fig. 1.

Figure 3 is a side elevation.

To enable others skilled in the art to make and use my invention, I will proceed to describe its construction and operation.

Fig. 1 is a top view of the damper in a horizontal position; it is composed of two metallic disks, the top disk placed directly over the lower one, and about an inch above it; these two disks are confined together at the journals marked A A. Now if this damper be placed in a pipe of suitable size, and at right angles with the pipe, it will wholly fill the space, so that no smoke can escape past the damper. To give passage to the smoke I remove a portion of each disk upon opposite sides. In fig. 2, the part removed from the one is shown at C, and B shows the part removed from the other disk. The smoke will now pass the pipe; when it meets the lower disk the smoke will all be thrown upon one side and pass the lower disk at the opening B. The smoke will now cross over to the opposite side of the pipe, between the disks, and escape upward through the upper disk at the opening C. This process will retard the smoke, and throw off much more heat than if passing upward unobstructed. To regulate the draught I place slide D, fig. 3, upon one of the disks, placing the slide flat upon the disk, and riveting them together at E, leaving the slide free to turn upon the rivet both outward and inward. I also put a stop upon the plate or disk at G, fig. 1. Now, to use the damper, place it in a vertical pipe of suitable size, rotating upon the journals A A, being vertical and parallel with the pipe, the slide being in the upper section, the stove now has the full draught of the pipe; turn the damper one-fourth round, and at right angles with the pipe, the slide being upon the plate to which it is attached, the smoke will now pass up on one side the pipe and through the lower plate, and cross over to the opposite side between the plates, and escape through the upper plate at the opening C. To close a part of the draught, tip down the side of the damper having the slide attached, till the slide will slide outward till it is checked by the stop G. Now bring it to a level, as before, and the draught will be partly closed. To wholly close the draught bring the damper to a vertical position, the slide being upward. Now turn the damper three-quarters round, in the direction that when one quarter turned the slide will be on the bottom of the plate. In passing round the slide will slide outward, and will sag down and pass under the stop G, and to the circle of the pipe, and when three-quarters round the pipe will be wholly closed for the night. Turn it a quarter more, or a full circle, and the stove has its full draught. I also place a spiral spring upon the journal, between the thumb-piece and pipe at H, to give a slight friction to prevent the damper from rotating of itself. This damper will not fill with soot or get out of order, and makes a great saving of fuel.

Claim.

What I claim, and desire to secure by Letters Patent, is—

A damper made of two parallel plates or disks, whose edges are cut away at opposite sides, and to one of which is pivoted, hinged, or adjusted, near the side thus cut away, a valve or slide, the whole device constructed so as to operate substantially as described.

EPHRAIM PARKER.
